Primary Examiner — Cynthia Underwood*(74) Attorney, Agent, or Firm* — Kirk A. Buhler; Buhler & Associates(57) **CLAIM**

The ornamental design for an anchor hook, as shown and described.

DESCRIPTION

FIG. 1 is a front side perspective view for an anchor hook showing my new design;

FIG. 2 is a front side view thereof;

FIG. 3 is a back side view thereof;

FIG. 4 is a top side view thereof;

FIG. 5 is a bottom side view thereof;

FIG. 6 is a left side view thereof;

FIG. 7 is a right side view thereof; and,

FIG. 8 is a perspective view thereof shown decreased in scale and in an environment of use.

The broken lines in FIG. 8 depict environmental subject matter of a rope and forms no part of the claimed design.

1 Claim, 4 Drawing Sheets---
